UNITED STATES PATENT OFFICE.

LOUIS JULLIEN, OF PASSY, FRANCE, ASSIGNOR TO JOSEPH WILD & CO., OF NEW YORK CITY.

DESIGN FOR A CARPET-PATTERN.

Specification forming part of Design No. 5,841, dated May 7, 1872.

Specification describing a new and original Design for Carpet, invented by LOUIS JULLIEN, of Passy, in the Department of the Seine, France.

The accompanying photograph fully illustrates my new design.

This invention relates to a new floral design for carpets and other fabrics; and con-

sists in the collection of the bunches of flowers with leaves interspersed, as shown.

I claim as my invention—

The floral design for carpets, as shown.

LOUIS JULLIEN.
